SHOWER CURTAIN

Nathaniel Gaines, South Orange, N. J.

Application May 31, 1941, Serial No. 395,926

5 Claims. (Cl. 160—388)

This invention relates to curtains, and more particularly to shower curtains of water-repellent, water proof or other types of material for use in bath rooms, both as a decorative feature and for preventing excessive splashing of the shower water.

The universal practice in constructing shower curtains for use in connection with shower bath attachments to bath tubs or with shower stalls wherein a curtain is employed to close off the shower has heretofore been to insert a plurality of metal grommets along the upper edge or hem of the curtain, at spaced points. These grommets, being metal, detract from the artistic appearance of the curtain and frequently they rust, causing unsightly rusty streaks on the curtain. They permit only of limited fixed points of suspension of the curtain from the pole or rod, which in a number of installations causes improper arrangement of the folds of the curtain, resulting in drooping and unsightly hanging of the curtain.

An object of the present invention is to provide a shower curtain which completely dispenses with the use of grommets, and of the various types of unsatisfactory structures which have been devised in an endeavor to hide them, and provides an attractive, artistic, practical curtain, embodying means for attaching supporting hangers or hooks thereto, which means also serves as a decorative feature of the curtain and provides for an unlimited variation in the number and placement of the connections of the hangers to the curtain, permitting support of the curtain at any of a number of points along its length so as to insure of proper and artistic hanging of the curtain.

Another object of the present invention is to provide a shower curtain as specified which has a series of loops along its upper edge made from a semi-flexible cord, bent sinuously to provide alternately opposed loops, one set of which serves to connect the cord to the curtain, while the other set serves the dual purpose of decorating the upper edge of the curtain and of providing means of connection between the curtain and the hangers. These loops being semi-flexible, embody sufficient rigidity to maintain their upright or erect position at all times, and resist stretching due to the weight of the curtain, which is supported from certain of them, and thus eliminates sagging of parts of the curtain, as well as sagging or "hanging over" of the loops which are not utilized in connection with the hooks for hanging the curtain.

With these and other objects in view, as may appear from the accompanying specification, the invention consists of various features of construction and combination of parts, which will be first described in connection with the accompanying drawing, showing a shower curtain of the preferred form embodying the invention, and the features forming the invention will be specifically pointed out in the claims.

10 In the drawing:

Figure 1 is a fragmentary view of a shower curtain constructed in accordance with the present invention.

Figure 2 is an enlarged cross-section taken on 15 the line 2—2 of Figure 1.

Figure 3 is an enlarged fragmentary longitudinal section taken on the line 3—3 of Figure 2.

Figure 4 is a fragmentary view of a modified form of the shower curtain.

Figure 5 is a cross-section taken on the line 20 5—5 of Figure 4.

Referring more particularly to the drawing, the combined decorative and supporting edging or crown is attached along the upper edge of the curtain body 1. It comprises, as shown in Figures 1 to 3 of the drawing, a cord 2, which may be made of braided, twisted, or woven fabric, or in any of the approved methods by which fabric cords are made. The cord 2 is treated, coated 25 or impregnated with a stiffening material which is not soluble in water, so as to impart a stiffness or semi-flexibility to the cord. Also, if it is desired, the cord 2 may be made of a drawn or extruded strip of any suitable plastic, or even of metal embodying non-rusting properties and in the form of a wire, without departing from the spirit of the present invention.

The cord 2 is arranged or bent sinuously 30 throughout its length, to provide alternate loops 3 and 4, which extend in opposite directions, with the loops 3 projecting above the upper edge of the curtain body 1, and the loops 4 overlapping the upper edge of the curtain body 1 and providing for attachment of the cord to the curtain body.

A binder strip 5 is positioned outwardly of the side of the cord 2, facing away from the curtain body 1, and is stitched to the curtain body and 35 the cord 2, to securely attach the cord and the binder strip to the curtain body and cover the loops 4 of the cord so as to provide an artistic appearance of the upper edge of the curtain. The loops 3 provide an artistic and attractive 40 edging for the top of the curtain body 1, and also

provide means for connecting suitable hangers (not shown) to the curtain for suspending it from a rod or pole (not shown).

By making the cord of semi-flexible or semi-rigid construction, the loops 3 will maintain their erect position at all times, whether they are used as the connecting loops to which the hooks are attached or not. It is to be understood, of course, that the hooks or hangers are to be attached to only certain of the loops, and not to all of them.

If it is so desired, for the purpose of facilitating the assembly of the curtain structure, a webbing or binder tape 5 may be folded over the loops 4, as clearly shown in Figure 2 of the drawing, and stitched thereto, prior to the attachment of the loops to the curtain top. Thus, the cord 2 will be maintained in its looped position and arrangement and may be more easily and readily stitched to the curtain top and binder strip 4.

In Figures 4 and 5 of the drawing a modified form of the invention is shown. In this construction, the upper edge of the curtain body 10 is folded over upon itself, as shown at 11, to provide a pocket extending longitudinally along the top of the curtain body. This pocket 12 opens along the upper edge of the curtain body 10 so as to permit the inverse loops 14 of the cord 15 to be inserted into the pocket for attachment to the curtain body by stitching. The upstanding loops 16 of the cord project beyond the upper edge of the curtain body and provide a decorative top edging for the curtain, and also means for connecting hooks or hangers to the curtain for suspending it from a rod (not shown).

If it is so desired, the cord 15 may be stitched to a binder tape 17 prior to its insertion into the pocket 12, so as to maintain the cord in its sinuous loop-forming position and facilitate the stitching of the cord to the curtain body.

Also, if it is so desired, a strip of suitable stiffening material, as indicated at 18, may be inserted into the pocket 12, and the two sides of the pocket 12, the strip of stiffening material 18, the binder strip 17 and the cord 15 may all be stitched together by the same lines of stitching, as indicated at 19.

Of course, it is to be understood that the binding strip 17 may be eliminated, without departing from the spirit of the present invention, and also that the stiffening strip 18 may be eliminated, and that either of these strips 17 or 18 may be employed without the other, without departing from the spirit of the present invention.

While in the drawing and in the foregoing description the decorative supporting edging is shown at the top edge of the curtain, it is to be understood that it may be placed below, or adjacent to the top edge of the curtain without departing from the spirit of the present invention.

It will be understood that the invention is not to be limited to the specific construction or arrangement of parts shown, but that they may be widely modified within the invention defined by the claims.

What is claimed is:

1. The combination with a curtain, of a deco-

rative supporting edging along the top edge of the curtain comprising a carrying strip, a semi-rigid cord bent in a sinuous manner to form a series of open loops and attached to said carrying strip in such manner as to provide a series of closed loops projecting beyond one edge of the carrying strip, the upper portion of the curtain being folded over upon itself to form a pocket extending along the top edge of the curtain, said carrying strip being inserted into said pocket and stitched to the curtain.

2. The combination with a curtain, of a decorative supporting edging along the top edge of the curtain comprising a carrying strip, a semi-rigid cord bent in a sinuous manner to form a series of open loops and attached to said carrying strip in such manner as to provide a series of closed loops projecting beyond one edge of the carrying strip, said cord being of sufficient rigidity and stiffness to maintain the loops in straight unbending position at all times, the upper edge of said curtain being flush with the upper edge of said carrying strip and covering one side of the carrying strip, and a binder strip covering the other side of the carrying strip and stitched to the carrying strip and curtain.

3. The combination with a curtain, of a decorative supporting top edge for the curtain comprising a cord bent in a sinuous manner to form a series of opposed loops, the upper portion of the curtain being folded to form a pocket extending along the top edge of the curtain, said cord being inserted into said pocket with alternate loops projecting out of the pocket and above the top edge of the curtain, and the other loops opposed to the alternate loops projecting above the curtain edge being inserted into the pocket and stitched to the curtain.

4. The combination with a curtain, of a decorative supporting top edge for the curtain comprising a cord bent in a sinuous manner to form a series of opposed loops, the upper portion of the curtain being folded to form a pocket extending along the top edge of the curtain, said cord being inserted into said pocket with alternate loops projecting out of the pocket and above the top edge of the curtain, and the other loops opposed to the alternate loops projecting above the curtain edge being inserted into the pocket and stitched to the curtain, said cord being made of fabric treated with a plastic composition to render it semi-rigid with sufficient body stiffness to maintain the loops in upright unbending position at all times.

5. The combination with a curtain, of a decorative supporting edging along the top edge of the curtain comprising a carrying strip, a cord bent in a sinuous manner to form a series of opposed loops and attached to said carrying strip in such manner as to provide a series of closed loops projecting beyond one edge of the carrying strip, said carrying strip being stitched to the top of the curtain with said loops projecting beyond the top edge of the curtain.
